UNITED STATES PATENT OFFICE.

JOSEPH SCHMEDINGHOFF, OF CINCINNATI, OHIO.

IMPROVEMENT IN FIRE-PLACE STOVES.

Specification forming part of Letters Patent No. 40,503, dated November 3, 1863.

To all whom it may concern:

Be it known that I, JOSEPH SCHMEDINGHOFF, of Cincinnati, Hamilton county, Ohio, have invented a new and useful Improvement in Fire-Places; and I do hereby declare the following to be a full, clear, and exact description thereof, reference being had to the accompanying drawings, making part of this specification.

This invention is intended to secure a complete utilization of the fire-heat, together with efficient ventilation and combustion of the smoke, the same means also tending to preserve the parts immediately in contact with the fire from too rapid destruction.

Figure 1 is a perspective section of a fire-place embodying my invention. Fig. 2 shows a portion of the same detached.

A is a chimney-back, and B its breast. C is the grate. D are passages for cold air, which, entering behind and at each side of the fire-place C, cool the inclosing-plates thereof and discharge into the fire numerous jets of heated air through orifices E, and thus assist combustion. The passages D, I style the "draft-passages."

Outside of and in the rear of the passages D is my ventilating-chamber F, which, admitting fresh air below, discharges it in a heated condition through a vantage, G, into the apartment.

The chamber F, near its upper rear portion, communicates by damper H with a chest, I, in the chimney J. One or more pipes, K, convey heated air from the chest I to distant portions of the building.

A damper, L, permits the escape of heated air directly into the chimney J whenever hot air is not required in the rooms.

N O are handles by which the dampers H and L are operated.

I claim herein as new and of my invention— The arrangement of fire-place C, draft-passages E, ventilating-chamber F, chest I, pipes K, chimney J, and dampers H L, the whole being combined and operating as described.

In testimony of which invention I hereunto set my hand.

JOSEPH SCHMEDINGHOFF.
